N. LONG.
PELT STRETCHER.
APPLICATION FILED FEB. 3, 1917.

1,232,059.

Patented July 3, 1917.

W. A. S. Sawyer. Attorney.

UNITED STATES PATENT OFFICE.

NOAH LONG, OF BAILEYS MILLS, OHIO, ASSIGNOR OF ONE-HALF TO E. A. LONG, OF BAILEYS MILLS, OHIO.

PELT-STRETCHER.

1,232,059.

Specification of Letters Patent.

Patented July 3, 1917.

Application filed February 3, 1917. Serial No. 146,474.

To all whom it may concern:

Be it known that I, NOAH LONG, a citizen of the United States, residing at Baileys Mills, in the county of Belmont and State of Ohio, have invented certain new and useful Improvements in Pelt-Stretchers, of which the following is a specification.

This invention relates to improvements in devices for stretching the pelts of fur bearing animals, and for like purposes, and has for one of its objects to provide a simply constructed device whereby the pelt may be uniformly stretched during the process of drying and curing, and which will apply 10 the strain uniformly to all parts of the pelt.

With these and other objects in view, the invention consists in certain novel features of construction, as hereinafter shown and described and then specifically pointed out 20 in the claims; and in the drawings illustrative of the preferred embodiment of the invention—

Figure 1 is a view of the improved device with the parts in withdrawn or collapsed position.

Fig. 2 is a view similar to Fig. 1 with the parts in stretched or extended position.

Fig. 3 is a plan view on an enlarged scale with the parts in section on the line 3—3 of 30 Fig. 2.

Fig. 4 is an enlarged sectional detail on the line 4—4 of Fig. 2.

Corresponding and like parts are referred to in the following description and indicated 35 in all the views of the drawings by the same reference characters.

The improved device comprises a main continuous rod or central member 10 having a push button 11 at one end and with a 40 plurality of prongs or pelt engaging points 12 at the opposite end. Attached to the member 10 near the terminal 12 is a supporting device adapted to pivotally or swingingly carry a plurality of radius bars or 45 arms, the latter in turn pivotally or swingingly connected to the stretcher members. The supporting device which is attached to the member 10 is shown formed of plates 13—14 having intermediate half sockets in which 50 the member 10 is received, and to which the members 13—14 are rigidly secured, as by rivets 15. The pivoted arms above referred to are represented at 16 and the stretcher members at 17, the latter being preferably 55 in flattened U shape transversely as shown

in Fig. 3, with the radius bars 16 pivoted at one end, as shown at 18, between the sides of the members 17. The outer edges of the members 17 are thus rounded so that they will not abrade or rupture the pelts in which 60 they are disposed.

At their inner ends the members 16 are pivoted at 19 between the plates 13—14 and at opposite sides of the rod 10. The members 16 thus serve as radius bars to enable 65 the stretcher members 17 to be moved outwardly away from the rod or shaft 10 and the plates 13—14.

Slidably disposed upon the rod 10 between the members 13—14 and the push button 70 member 11, are other plates 20—21 which are duplicates of the plates 13—14 except that they are not riveted or otherwise fastened to the shaft 10, but are slidable thereon. A plurality of the radius bars 16 are 75 disposed in spaced relation and pivoted at 22 between the sides of the stretcher members 17 and likewise pivoted at 23 between the plates 20—21 and at opposite sides of the rod. The bars which are associated with the plates 20—21 and the stretcher members 17 operate to move the stretcher members outwardly away from the rod 10 when the plates 20—21 with their attached bars 16 are moved toward the button member 11, 80 or the button member 11 moved toward the plates 20—21. By this arrangement the members 20—21. By this arrangement the device may be so manipulated as to cause the parts to assume the relative position shown in Fig. 2, or at any intermediate point 85 between the positions shown in Figs. 1 and 2.

The members 17 are provided with a plurality of spurs 27 at the ends farthest from the prongs 12, over which the larger open-end of the pelt is stretched when applied to 90 the device, and similar spurs 28 project from the member 21 to engage the central portions of the pelt, to assist in holding it in stretched position.

The pelt to be stretched is disposed over 100 the implement when the parts are arranged in their withdrawn position, or as shown in Fig. 1, with the "nose" portion of the pelt engaged by the prongs 12 of the rod 10, and the opposite portion of the pelt stretched 105 over the points 27.

The rod 10 is then forced longitudinally by pressure applied to the button 11 and the plates 20—21 moved toward the button 110 or held stationary while the rod is forced

between them. These movements will cause the radius bars 16 to move toward a position at right-angles to the rod 10, or until the members 17 stretch the pelt thereon, the distance which the bars 17 are moved depending upon the size of the pelt. The pelt may thus be stretched to any required extent, and thus maintained until it is fully dried or "cured." When the radius bars 16 which are associated with the movable plates 20-21 are disposed at right angles to the rod 10 as shown in Fig. 2, they "lock" the stretcher members in open position, consequently when the pelt is of a size to be fully 15 distended when the stretchers are thus arranged, no other locking means will be required. When smaller pelts are to be stretched it will be necessary to employ a suitable locking means to hold the stretchers in distended position.

The locking means comprises a plurality of notches 24 in spaced relation in the rod 10, and rigidly secured between the adjacent portions of the plates 20-21 is a yieldable catch device 25 having a tongue 26 adapted to engage in the notches 24 one at a time. By this means when the rod 10 is moved longitudinally of the members 20-21, or the members 20-21 moved longitudinally 25 of the rod, the members 25-26 will engage the adjacent notch and hold the rod in position relatively to the members 21-22, and correspondingly lock the stretcher members 17 in their distended position.

35 The parts are wholly of metal as light as possible consistent with the strains to which they will be subjected, and are preferably galvanized, plated or otherwise protected from oxidation, and to likewise protect the 40 pelts from injury by contact with the metal parts.

Having thus described the invention, what is claimed as new is—

1. A device of the class described comprising a continuous central member, stretcher members, a plurality of radius bars in spaced relation and pivotally connected to said member at opposite sides thereof and to said stretcher members, a member movable relatively to said longitudinal member, and a plurality of radius bars disposed in spaced relation and pivoted respectively to said movable member at opposite sides thereof and to said stretcher members.

55 2. A device of the class described comprising a continuous central member, stretcher members, a plurality of radius bars

in spaced relation and pivotally connected to said member at opposite sides thereof and to said stretcher members, a member movable relatively to said longitudinal member, a plurality of radius bars disposed in spaced relation and pivoted respectively to said movable member at opposite sides thereof and to said stretcher members, and means 60 65 for locking said movable member to said central member.

3. In a device of the class described, a continuous central member, coacting plates disposed in spaced relation and rigidly connected to said central member at opposite sides thereof, stretcher members, a plurality of radius bars disposed in spaced relation and pivoted respectively to said stretcher members and between said plates and at opposite sides of the central member, other coacting plates disposed in spaced relation and movable upon said central member at opposite sides thereof, a plurality of radius bars disposed in spaced relation and pivoted 70 75 respectively to said stretcher members and between said last mentioned movable plates and the opposite sides of said central member.

4. A device of the class described comprising a continuous central support, oppositely curved stretcher members, a device movable longitudinally of the said support, radius members of varying lengths disposed in spaced relation and pivotally coupled respectively to said stretcher members and to said support at opposite sides thereof, and a plurality of radius members of uniform length disposed in spaced relation and pivotally coupled respectively to said movable 80 85 device at opposite sides thereof and to said stretcher members.

5. A device of the class described comprising a continuous central support, oppositely curved stretcher members, a device 100 movable longitudinally of the said support, radius members of varying lengths disposed in spaced relation and pivotally coupled respectively to said stretcher members and to said support at opposite sides thereof, a 105 plurality of radius members of uniform lengths disposed in spaced relation and pivotally coupled respectively to said movable device at opposite sides thereof and to said stretcher members, and means for locking 110 said movable member to said support.

In testimony whereof I affix my signature.

NOAH LONG. [L. S.]

It is hereby certified that in Letters Patent No. 1,232,059, granted July 3, 1917, upon the application of Noah Long, of Baileys Mills, Ohio, for an improvement in "Pelt-Stretchers," an error appears requiring correction as follows: In the grant and in the heading to the printed specification the name of the assignee was erroneously written and printed as "E. A. Long," whereas said name should have been written and printed as *E. A. Lynch*, as shown by the record of assignments in this office; and that the said Letters Patent should be read with this correction therein that the same may conform to the record of the case in the Patent Office.

Signed and sealed this 14th day of August, A. D., 1917.

[SEAL.]

R. F. WHITEHEAD,
Acting Commissioner of Patents.

Cl. 149—21.
